VIVIAN J. PEARSE, OF EVERETT, WASHINGTON.

APPARATUS FOR TREATING PATIENTS BY BODILY MOVEMENTS.

Application filed September 29, 1920. Serial No. 413,517.

The general object of this invention is to provide novel treatment for various abnormal physical conditions, for example, the undue accumulation of fatty matter in the human body, and this treatment involves slowly rotating the body of the patient about a longitudinal axis. From many possible ways of carrying out the general idea of the invention devices shown in the drawings have been selected.

In these drawings, which are largely diagrammatic,

Fig. 1 is a side elevation of a form of apparatus which may be used.

Fig. 2 is an elevation looking from the left in Fig. 1.

Fig. 3 is a diametrical longitudinal section of a slightly modified cylinder which may be used instead of that shown in Fig. 1.

In these figures, A represents a drum open at each end and made of wood, canvas, or other material. The upper side of the drum wall is gripped between parallel rollers B, B' having shafts C, C', yieldingly pressed together by springs H and revoluble in bearings D, D'. The shafts are connected by gears E, E' and one of them bears a driving pulley F or is connected to any suitable source of power. The interior of the drum is preferably provided with low projections O, which may be cushion-like, so that the drum surface may not slip on the body of the patient in the cylinder and so fail to produce the desired rotation.

If while the patient lies extended inside the drum rotating power be caused, by the patient or another, to act upon the rollers the drum will be rotated and will in its own rotation cause the body of the patient to rotate, the drum tending to raise the body and gravity causing it to roll toward the lowest part of the drum. This affords a sort of mild massage, but the action and results are very different from anything heretofore produced, so far as I am aware. Obviously, ordinary kneading, surface rubbing, percussion, and the like are not equivalent ways of massaging, for here every portion of the body is urged by gravity to move in constantly changing directions, and each limb and each internal organ is moved, or impelled in different directions. This motion modifies the circulation, and the ab-

dominal and thoracic organs are all acted upon as they cannot be by ordinary methods. Practical use of the apparatus shows that the nervous system is usually benefited, that assimilation and elimination of undesirable matter both become more active, and that there is a marked reduction in fatty accumulations. The method set forth is often used solely to reduce corpulence, and while it is effective it incidentally and necessarily improves the general physical condition instead of being injurious as are many fat-reducing expedients.

It is plain that the massage will be more or less gentle according to the speed of rotation, and that in certain cases the rotation of body may be extremely slow, gently shifting the blood without the least muscular or other effort on the part of the patient.

Very similar results are reached by using the slightly modified devices of Fig. 3. Here a drum I has end spiders J to which the parts L of the power shaft are attached, and if desired, a large door K through which one may enter and leave the drum. Other expedients for rolling the drum may be adopted, the essential being that the reclining person inside shall be rotated, whatever the means for applying rotating force.

What I claim is:

1. In therapeutic devices for mechanically treating the human body, the combination with a concave member adapted to support extended in horizontal position the body of a patient to be treated and to resist its slipping on the member, of means for forcibly moving said member relative to said body and transversely with respect to the longitudinal axis thereof to roll said supported body about said axis, whereby the position of said body is successively reversed.

2. In a therapeutic device, the combination with a hollow receptacle having a yielding interior surface adapted to support the free body of a patient stretched out therein and prevent its slipping on said surface, and means for slowly advancing the receptacle wall beneath the body, compelling the latter to rotate.

3. In a therapeutic device, the combination with a hollow cylinder having a cushion-like interior surface adapted to prevent

ready slipping of a patient thereon, and means for slowly rotating the cylinder, whereby the patient is gently raised with the ascending wall of the cylinder and rolled in a contrary direction by gravity.

4. In a therapeutic device, the combination with a hollow receptacle having a cushion-like interior surface and adapted to con-

tain the prone body of a patient, of power driven rollers engaging and advancing the upper side of the receptacle wall, whereby the body of the patient may be slowly rotated with respect to its longitudinal axis.

In testimony whereof I hereunto affix my signature.

VIVIAN J. PEARSE.
